Des. 222,454
Patented Oct. 26, 1971

222,454

ELECTRODE CLAMP

Jack Beeber, 35 Seacoast Terrace,
Brooklyn, N.Y. 11235

Filed July 17, 1970, Ser. No. 23,989

Term of patent 14 years

Int. Cl. D24—02

U.S. Cl. D16—1

Fig. 1.

Fig. 2.

Fig. 3.

FIG. 1 is a front perspective view of an electrode clamp, embodying the features of my new design,

FIG. 2 is a side elevation view, and

FIG. 3 is a front elevation view thereof.

What I claim is:

The ornamental design for an electrode clamp, substantially as shown and described.
